UNITED STATES PATENT OFFICE.

JOHN F. MEIGS AND ROBERT P. STOUT, OF SOUTH BETHLEHEM, PENNSYLVANIA, ASSIGNEES
TO BETHLEHEM STEEL COMPANY, OF SOUTH BETHLEHEM, PENNSYLVANIA, A CORPO-
RATION OF PENNSYLVANIA.

AUTOMATIC MEANS FOR CONTROLLING MOVEMENTS OF GUN-RAMMERS.

No. 900,755.

Specification of Letters Patent.

Patented Oct. 13, 1908.

Application filed May 22, 1907. Serial No. 375,064.

To all whom it may concern:

Be it known that we, JOHN F. MEIGS and ROBERT P. STOUT, citizens of the United States, and residents of South Bethlehem, 5 county of Northampton, State of Pennsylvania, have invented certain new and useful Improvements in Automatic Means for Controlling Movements of Gun-Rammers, of which the following is a specification.

10 Our invention relates to that class of rammers which are operated by power and more especially to that class in which the rammer is actuated from a driving shaft operated by a suitable motor, and consists in means to 15 automatically regulate the movements and extent of movements of the rammer, as fully set forth hereinafter and as illustrated in the accompanying drawings, in which

20 Figure 1 is an elevation of our improved apparatus looking towards the breech of the gun; Fig. 2 is a side elevation of the apparatus and part of the breech of the gun; Fig. 25 3 is a plan diagram showing the different relations of the contacts of the controller and those of the motor, and Fig. 4 is a sectional detached view of the controller. Fig. 5 illustrates diagrammatically the wiring and electrical contacts connected with the controller and motor.

30 The gun X is provided with any suitable mechanical rammer constructed and arranged to be reciprocated from a driving shaft H through the medium of any suitable gearing and connections, the rammer also 35 being of any desired character, but the construction shown is substantially of the character of that set forth in Letters Patent issued to us, No. 804,243, dated November 14, 1905. In this construction there is a frame

40 1, 2, supported by the gun and supporting interlocking chains which are suitably guided in the frame and connected at their ends to the rammer, substantially as set forth in said patent, the proper movements being 45 imparted to the rammer chains from a shaft K, and suitable gear, as indicated at 3, 4. As the details of these parts constitute no part of our present invention and as they will be understood by reference to the preceding patent, it will not be necessary to further describe the same, except to point out 50 that the shaft K is telescopic, consisting of sections 5, 6, 7, turning together, the former sliding in the latter, which are tubular, and

the latter turning in a bracket 8 having 55 trunnions swinging in standards 9, 9 of a casing Y which is carried with the gun. This construction of the shaft K permits the gun to be swung on its trunnions to any desired elevation without affecting the driving 60 mechanism.

The shaft K is driven from the shaft H through the medium of gears 10, and movement is imparted to the shaft H from a motor M, which may be of any suitable 65 character, and which is started and stopped through the medium of a controller N. Obviously the character of this controller will depend upon the character of the motor. If the motor is a hydraulic motor, or an air or 70 steam engine, the controller will be a valve. If, as shown, the motor is electric, the controller which is the usual form of drum controller will be provided with circuit makers and breakers diagrammatically illustrated in 75 Fig. 5. In either case the controller is of such a character that it will serve, by the adjustment of its parts by hand, to start the motor in either direction, and to reverse it and stop it by the proper automatic shifting 80 of the parts. For this purpose there is combined with the controller what we term shifting means, the same consisting of means whereby after the valve or switch is set to start the engine, it is again shifted to reverse it, and again shifted to stop it, and the parts are so constructed that the first of these movements, to wit, the movement of the shifting device to start the engine, may be effected by hand, while the reversing and 85 stopping movements are automatic.

In order that the rammer may have its movements proportioned to the work to be done, as for instance in carrying in the projectile, which takes the longest stroke, and carrying the charge, which takes a shorter stroke, the shifting means is so constructed as to secure this result. The devices to effect this result and thereby control the movements of the driving shaft H may be variously constructed and arranged, but as shown, the shifting means consists of a shaft 12 carrying a pinion 13, and spur wheel 14 on a shaft J upon which are contacts A, B and C, radially arranged equi-distant from each other upon the shaft, but the contact C is in a more elevated position than the other contacts.

Upon the shaft H are carried three contacts D, E, F, in such manner as to rotate with the shaft and also to move to and from the contacts upon the shaft J. As shown, 5 the contacts D, E, F, are secured adjustably upon a sleeve G, by bolts *t*, said sleeve being splined so as to slide on and turn with the shaft H and said sleeve has a threaded end adapted to a threaded socket I in one of 10 the standards 9 so that as the shaft H turns in one direction the contacts D, E will be carried towards the shaft J and the contact F from the said shaft, while the rotation of the shaft H in the opposite direction will carry 15 the contact F toward the shaft J and the contacts D, E away from it. The contact E is shorter than the contacts D and F so as only to make contact with the lower contacts A and B upon the shaft J, while the 20 contacts D and F are of greater length, the contact D being furthest from the shaft J and will engage the more elevated contact C. The shaft J is geared with the shaft 12 of the controller by means of gears 13, 14 proportioned to insure one rotation of the shaft 25 12 to one-third of a rotation of the shaft J, and at the upper end of the shaft 12 is a handle V by means of which it may be turned by hand, and within the casing of 30 the controller the shaft 12 carries a switch arm 29 carrying usual brushes 40 and which on the rotation of the shaft may be brought opposite the curved terminals 19 to complete a circuit with the motor in one direction so 35 as to carry the rammer forward and then opposite a break *v*, which breaks the circuit, and then opposite terminals 20 which are then in circuit with the motor to reverse the same, and then opposite an extended break. 40 *w*. When the upper brushes 40, diagram Fig. 5, are upon the upper pair of terminals 19 the circuit is through *a*, through the upper brushes 40 and terminals 19 to the line *c*, through the armature and brushes 40^a and 45 through lower terminals to the line *e* and field, thereby rotating the armature in one direction. When the brushes 40 are upon the terminals 20, the circuit is through the line *a* and upper brush and terminal 20 to 50 the terminal 20^a and upper of the lower two brushes 40^a to the armature, through the line *c* and terminal 20^b to the terminal 20^c and lower of the pair of brushes 40^a to the line *e* and field, whereby the armature is rotated 55 in the opposite direction.

The arm 29 occupies such position upon the shaft 12 in respect to the position of the contact arms A, B, C upon the shaft J that when the arm 29 is in the position shown in 60 Fig. 4 the arms A, B, C will be in the position shown in Fig. 3, and the radial lines of the former figure indicate the different positions taken by the circuit making and breaking arm 29.

65 Assuming the different arms to be in the

position shown in Figs. 3 and 4, the apparatus will be at rest. If now the operator swings the shaft 12 by means of the handle V in the direction of the arrow, Fig. 4, so as to carry the arm 29 one-third of a revolution from the line 16 to the line 17, the shaft 70 J will be rotated one-ninth of a revolution and the arm C will be carried to the position of the line C'. On making the circuit including the arm 29 and the terminal 19 the 75 motor will start to carry the rammer into the gun, which rammer will move at full speed forward, and this operation will continue until the long contact D moving toward the shaft J in the direction of its arrow strikes 80 the arm C and rotates it to the position indicated by the line C''. At the termination of this movement the controller arm 29 which has moved rapidly past the break at *v* will have moved from the position 17 to the position 85 18, and on to the terminal 20 so that the motor is reversed and carries the rammer at full speed to the rear. This reverse action of the motor carries the contact F toward the shaft J and continues until the contact F 90 strikes on arm A now in the position shown by the line A'' and moves it to the position of the arm B in the drawing, Fig. 3, this movement turning the shaft 12 to carry the controller arm 29 to the position shown in 95 Fig. 4, thereby breaking the circuit and arresting the motor, with the rammer drawn fully to the rear and the arm B in the position of the arm C, Fig. 3 (and as shown in Fig. 1). The above described full forward 100 movement of the rammer serves to introduce the projectile, and it now becomes necessary to impart a shorter forward movement to carry in the charge of powder.

The controller shaft 12 is again rotated by 105 hand, which brings the arm B to the position indicated by the line C'. On the operation of the motor the shorter and nearer contact E will be brought against the arm B and will carry the latter to the position of the line C'', but as the contact E is nearer the shaft J than the contact D, the motor will be sooner reversed in its movement so that the stroke of the rammer is shorter than before and on the reversal the contact F is carried towards the shaft J and will then be brought against the arm C now in the position of the line A'', and will turn the shaft and cause the circuit to be broken and the motor to be arrested as before.

For the third stroke of the rammer after being started again by hand the contacts E and F act upon the arms A and B to secure another short stroke. The extent of motion of the parts to carry the contact arms A, B, 125 C, to different positions need not be equal, but must correspond to the locations of the circuit making and breaking terminals of the controller. In the construction shown the two powder strokes are of the same 130

length as the second section of the charge carries ahead of it the first section to its final position.

The strokes of course could be readily varied by a suitable adjustment of the parts and using a suitable number of contacts on the shaft H of different lengths. As it may be necessary at times to rotate the shaft 12 of the controller by hand when one of the contacts D, E and F is in a position to interfere, each of the arms A, B, and C is provided with a pivoted terminal 31 capable of folding over when brought against the back side of contacts D, E or F.

15 While the different lengths of strokes may be secured by arranging the contacts D, E at different distances upon the shaft J, it will of course be evident that the same result might be effected by other means, and the 20 contacts or stops of the motor secured to the sleeve G by means of set screws or other adjusting devices to permit them to be shifted to vary the length and relation of the strokes, and the contacts A, B, C may also be adjustable in like manner upon the shaft J.

Where there are two guns in a turret the rammer of the second gun is operated from a second motor M'.

Without limiting ourselves to the precise construction and arrangement of parts shown and described, we claim as our invention:

1. The combination with a gun, a rammer and devices connected with the rammer to communicate movement to the same, of a motor for operating the said devices, a controller for the motor, and means connected with the motor to be moved thereby and interposed between the motor and the said devices to operate the controller.

2. The combination with a gun, a mechanically operated rammer and motor, of a controller for the motor and contact devices and means for moving them from the 45 motor arranged between the motor and the rammer, and connections between said devices and the controller.

3. The combination in rammer actuating mechanism for guns, of a driving shaft and means connecting it to operate the rammer, means for rotating said shaft, a controller whereby the rotating means is stopped, started and reversed, a shifting device for said controller, contacts connected with the 55 controller and contacts and means for swinging them from the driving shaft, the latter contacts arranged to engage contacts of the shifting device to carry the latter to its different positions.

60 4. The combination in rammer actuating mechanism for guns, of a driving shaft and means connecting it to operate the rammer,

means for rotating said shaft, a controller whereby the rotating means is stopped, started or reversed, a shifting device for 65 said controller, and adjustable contacts deriving their movements from the driving shaft and arranged to engage the shifting device at different intervals.

5. The combination in rammer actuating mechanism for guns, of a driving shaft and means connecting it to operate the rammer, means for rotating said shaft, a controller and connections whereby the rotating means is stopped, started or reversed, a shifting 75 device for said controller, and a plurality of contact devices arranged independently of the rammer and in different positions to shift the shift device to different positions to reverse and stop the rammer.

80 6. The combination with the rammer and driving shaft and connections between the rammer and shaft, of a motor and control device therefor provided with electrical contacts, a shifting device for shifting the 85 contacts of the controller, and contact devices movable to and from the shifting device as the shaft rotates, and arranged at different distances therefrom to automatically reverse and vary the length of the suc- 90 ceeding strokes of the rammer.

7. The combination with the rammer, shaft H, motor and connections between the shaft and rammer, of a controller for the motor, a shift device for the controller provided with radial stops set in different positions, and contacts set in different positions arranged to rotate with the shaft and movable to and from the stops of the shifting device.

100 8. The combination with a rammer, shaft and connections, of a motor, a control device and a shifting device having a shaft J and radial contact arms at different heights, a sleeve splined to the shaft H to turn therewith, means for moving the sleeve longitudinally upon the shaft and contact arms carried by the sleeve, at different distances from the shaft J, for the purpose set forth.

9. The combination with the rammer and driving shaft of an intermediate shaft K for conveying movement from the driving shaft to the rammer devices, the said shaft K consisting of telescopic sections, the sections swinging about the axis of the driving 115 shaft, for the purpose set forth.

In testimony whereof we affix our signatures in presence of two witnesses.

JOHN F. MEIGS.
